UNITED STATES PATENT OFFICE.

VERNON ROYLE, OF PATERSON, NEW JERSEY.

REGISTERING AND SQUARING MACHINE.

Application filed June 28, 1922. Serial No. 571,398.

To all whom it may concern:

Be it known that I, VERNON ROYLE, a citizen of the United States, and resident of Paterson, in the county of Passaic and State 5 of New Jersey, have invented a new and useful Improvement in Registering and Squaring Machines, of which the following is a specification.

This invention relates to registering and 10 squaring machines, with the object in view of providing a machine which is fitted with means for brilliantly illuminating the work (negative) from beneath, and also for intensifying the illumination at any desired 15 portion of the work.

Another object consists in providing such an apparatus which contains certain improvements in the form, construction and arrangement of the several parts, whereby 20 the above named and other objects may be effectively attained.

A practical embodiment of my invention is represented in the accompanying drawings, in which

25 Fig. 1 represents a plan view of a portion of the apparatus with my improved structure applied thereto, certain of the parts being broken away to show others below.

Fig. 2 represents a detail horizontal section, showing the illuminating and reflecting means in plan view.

Fig. 3 represents an enlarged detail vertical section taken in the plane of the line III—III of Fig. 1, looking in the direction 35 of the arrows.

This invention is illustrated as applicable to the registering and squaring machine which forms the subject matter of my United States Patent No. 1,450,608, dated

40 April 3, 1923, and reference is hereby made to that patent for detailed illustration and description of the said machine and the manner in which the present invention is applied thereto.

45 The present apparatus includes a table top 8 which is translucent and means is provided for thoroughly illuminating the work (negative) 12. The means comprises a pair of electric lights 67 which are fast in reflectors 68 (see Figs. 2 and 3) that are secured to brackets 69 which latter are fixed at opposite sides of the frame 7 by screws 70. These reflectors may be composed of suitable sheet metal such as polished aluminum, and it will be noted that the reflectors 55 pass around the outside of the lights and

project inwardly and downwardly beneath the lights so as to reflect the light upwardly. In order to more brilliantly reflect the light and to be able to intensify the illumination 60 of the work at any desired portion thereof, I have provided a pair of reflecting mirrors 71, which are hinged on a common pintle 72 which is mounted in lugs 73 depending from the frame 7, as clearly shown in Figs. 65 2 and 3. It will be observed that the lights 67 are elongated in form and arranged with their sides toward the translucent top 8, reflectors 68 and mirrors 71. These reflecting mirrors 71 project downwardly and outwardly 70 so as to be complementary to the reflectors 68, and their angularity may be varied by adjusting rods 74. Each of these rods is rotatably mounted in but fixed against longitudinal movement in sleeves 75 75 which are pivoted at 76 in the sides of the frame 7. The extremities of the rods 74 are threaded into tapped sleeves 77, which are pivoted at 78 on the edges of the reflecting mirrors 71. Each mirror has a 80 rod 74 connected to it and the said rods are located at opposite sides of the frame 7. Milled heads 79 are pinned to the upper ends of the rods 74 for manual operation thereof. It will be clear that, by changing 85 the angularity of the mirrors, the angle of reflection will be changed so as to vary the intensity of illumination of different portions of the work. The wires (not shown) for the lights 67 may be led from a suitable 90 source of current supply through an opening in the base (not shown), a tube 80, composed of insulating material, located within the pillar 3, and thence through a pair of branch tubes 81, also composed of insulat- 95 ing material, and leader 82 to the lights 67.

It will be understood that various changes may be resorted to in the form, construction and arrangement of the several parts without departing from the spirit and scope 100 of my invention; and hence, I do not intend to be limited to the details herein described, except as they may be specifically included in the claims.

What I claim is:

1. A registering and squaring machine comprising, a translucent table for holding the work, lighting means beneath the table, and a pair of adjustable hinged reflectors.
2. A registering and squaring machine 110 comprising, a translucent table for holding the work, lighting means beneath the table,

an adjustable swinging reflector, and a fixed reflector complementary to the said swinging reflector.

3. A registering and squaring machine comprising, a translucent table for holding the work, a light beneath the table and at each side thereof, and a pair of adjustable reflectors arranged beneath the table and between the lights.

10 4. A registering and squaring machine comprising, a translucent table for holding the work, a light beneath the table and at each side thereof, a pair of adjustable reflectors arranged beneath the table and between the lights, and a pair of fixed reflectors beneath the table and outside of the lights.

20 5. A registering and squaring machine comprising, a translucent table for holding the work, a light beneath the table and at the side thereof, an adjustable reflector arranged beneath the table, and a fixed reflector beneath the table and outside of the light, said fixed reflector extending around beneath the light and downwardly toward the adjustable reflector.

25 6. A registering and squaring machine comprising, a translucent table for holding the work, a light beneath the table and at each side thereof, a pair of adjustable reflectors arranged beneath the table and between the lights, and a pair of fixed reflectors beneath the table and outside of the lights, said fixed reflectors extending around

beneath the lights and downwardly toward the adjustable reflectors and said adjustable reflectors extending downwardly toward the fixed reflectors.

35 7. A registering and squaring machine comprising, a translucent table for holding the work, a light beneath the table and at the side thereof, an adjustable reflector arranged beneath the table, and a fixed reflector beneath the table and outside of the light, said fixed reflector extending around beneath the light and downwardly toward the adjustable reflector, and said light being elongated and arranged with its side toward the table and said reflectors.

40 8. A registering and squaring machine comprising, a translucent table for holding the work, a light beneath the table and at each side thereof, a pair of adjustable reflectors arranged beneath the table and between the lights, and a pair of fixed reflectors beneath the table and outside of the light, said fixed reflectors extending around beneath the lights and downwardly toward the adjustable reflectors, said adjustable reflectors extending downwardly toward the 55 fixed reflectors, and said lights being elongated and arranged with their sides toward the table and said reflectors.

45 In testimony, that I claim the foregoing as my invention, I have signed my name 60 this 8th day of June, 1922.

VERNON ROYLE.
